His ATTORNEY.

UNITED STATES PATENT OFFICE.

FRED R. TAISEY, OF INDIANAPOLIS, INDIANA, ASSIGNOR TO THE TAISEY PNEUMATIC SERVICE COMPANY, OF INDIANAPOLIS, INDIANA, A CORPORATION OF INDIANA.

INLET FOR PNEUMATIC-DESPATCH TUBES.

SPECIFICATION forming part of Letters Patent No. 705,884, dated July 29, 1902.

Application filed October 14, 1901. Serial No. 78,558. (No model.)

To all whom it may concern:

Be it known that I, FRED R. TAISEY, of Indianapolis, county of Marion, and State of Indiana, have invented a certain new and useful Inlet for Pneumatic-Despatch Tubes; and I do hereby declare that the following is a full, clear, and exact description thereof, reference being had to the accompanying drawings, in which like numerals refer to like parts.

10 The object of this invention is to provide means for introducing a carrier into a pneumatic-despatch tube without any admission of air through the inlet. The admission of air when a carrier is inserted into a pneumatic-despatch tube weakens the force of the air-current in the tube and temporarily checks it and the other carrier-boxes that may be in transit through the tube.

15 My invention is a simply and conveniently operative means for introducing the carrier without affecting the movement and force of the air-current within the tube.

20 The nature of this invention will be understood from the accompanying drawings and the following description and claims.

25 In the drawings, Figure 1 is an elevation of the inlet for a pneumatic-despatch tube and a portion of the tube, parts being broken away and in section and a carrier being in position for introduction into the tube. Fig. 2 is a central vertical section of what is shown in Fig. 1 with the carrier omitted. Fig. 3 is a section on the line 3 3 of Fig. 2, the crank being shown in dotted lines and broken.

30 In the drawings, 10 represents a support for the mounting of the device.

35 11 is a pneumatic-despatch tube.

I provide an inlet-chamber in the inlet-tube 12 and the valve-chamber 13. Said valve-chamber 13 contains the lower valve 14.

40 15 is a carrier.

The inlet-chamber is closed at its upper end by a valve or lid 16, pivoted at one side at 17 to the inlet-tube 12 and held closed by the spring 18, coiled about the pivot-pin 17.

45 19 is a finger-piece for opening the upper valve or lid.

The lower valve 14 is a horizontally-oscillating plate with a shank secured to the shaft

20, the lower end of which shaft has a bearing at 21 in the bottom of the valve-chamber 13, and the upper end has a bearing in the base 22 of the inlet-tube 12. Said valve has a leather washer 23 secured on its under side, and it is held normally over and closing the 55 passage-way from the valve-chamber 13 into the pneumatic tube 11 by means of the spring 24, coiled about the shaft 20. Said valve is moved from its normal position by the 60 crank 25.

The valve 14 has an upwardly-extending collar 26 to support the end of the carrier, as shown in Fig. 1. It is provided with a slot or notch 27 on one side to permit the lateral movement of the valve when a carrier having 65 a pin 28 is resting on the collar 26, as appears in Fig. 1. The valve-chamber 13 has a downwardly-extending sleeve 29, in which the upper end of the despatch-tube 11 is secured. In the bottom of the valve-chamber 13 a rib 70 or upward extension 30 is provided as a track to support the valve 14 and washer 23 during the lateral movement of the same from the position shown in full lines in Fig. 3 to the position shown in dotted lines. 75

The operation is as follows: The lid or valve 16 is elevated into an open position and the carrier 15 dropped into the inlet-chamber and the lid or valve 16 released. The lid or valve will then close the upper end of the inlet-chamber and the carrier 15 will rest endwise on the collar 26 of the valve 14, as shown in Fig. 1. Then the crank 25 is moved in the direction of the arrow in Fig. 3, causing the valve 14 to be moved from over the entrance 80 to the despatch-tube 11, whereupon the carrier 15 will drop into and enter said tube. The crank 25 is then released, and the spring 24 throws the valve 14 back to close the entrance 85 to said despatch-tube 11. 90

From this explanation it is obvious that while the carrier 15 is being inserted into the inlet-chamber, and after the upper end of the inlet-tube is closed and the lower valve is opened to permit the carrier to enter the despatch-tube no appreciable amount of air will pass from the inlet-tube into the despatch-tube. Hence the carrier can be introduced 95

into the despatch-tube without affecting the force of the current therein or the movement of any other carriers that may be in the tube.

What I claim as my invention, and desire 5 to secure by Letters Patent, is—

1. An inlet for a pneumatic-despatch tube consisting of an inlet-chamber, a spring-closed lid or valve at the outer end thereof, a spring-closed valve for closing the outlet from said 10 chamber, and means for moving said last-named valve laterally out of a closing position.

2. An inlet for a pneumatic-despatch tube consisting of an inlet-tube adapted to serve 15 as a guide for a carrier, a valve-chamber secured to the inner end of said tube which is extended at a right angle from said tube, a valve for closing the outlet from said valve-chamber that is pivotally mounted, and means 20 outside the valve-chamber for oscillating said valve.

3. An inlet for a pneumatic-despatch tube consisting of an inlet-tube, a valve-chamber secured to the inner end of said tube which 25 is extended at a right angle from said tube, a valve for closing the outlet from said valve-chamber that is pivotally mounted, means outside the valve-chamber for oscillating the

valve therein, and a rib or track in said casting upon which said valve moves in its oscillation.

4. An inlet for a pneumatic-despatch tube consisting of an inlet-chamber, a valve for closing the outer end thereof, a valve for closing the inner or outlet end thereof, means 35 on the latter valve adapted to support the carrier out of contact with the valve after the carrier has been inserted into said chamber, and external means for moving said valve out of the path of the carrier.

5. An inlet for a pneumatic-despatch tube including an inlet-chamber with an outlet therefrom to the despatch-tube, a valve for closing said outlet, means for moving said valve laterally to open said outlet, and a collar on said valve to support a carrier before the valve is actuated, said collar being slotted 45 on one side substantially as shown.

In witness whereof I have hereunto affixed my signature in the presence of the witnesses 50 herein named.

FRED R. TAISEY.
